CLAIM

The ornamental design for a video game tote case, substantially as shown and described.

DESCRIPTION

FIG. 1 is a perspective view of a video game tote case showing our new design in an open condition;

FIG. 2 is a top plan view thereof;

FIG. 3 is a front elevational view thereof in a closed condition;

FIG. 4 is a front elevational view thereof with the legs inserted and set up for use; and

FIG. 5 is a top plan view of FIG. 3, the bottom plan view being a mirror image thereof.

FIG 5

FIG 4
